UNITED STATES PATENT OFFICE

BURGESS DARROW, OF AKRON, OHIO, ASSIGNOR TO THE GOODYEAR TIRE & RUBBER COMPANY, OF AKRON, OHIO, A CORPORATION OF OHIO

DESIGN FOR A TIRE

Application filed February 27, 1931. Serial No. 38,848. Term of patent 14 years.

To all whom it may concern:

Be it known that I, BURGESS DARROW, a citizen of the United States, residing at Akron, in the county of Summit and State of Ohio, have invented a new, original, and ornamental Design for a Tire, of which the following is a specification, reference being had to the accompanying drawings, forming part thereof.

Fig. 1 is a fragmentary perspective view of a pneumatic tire having a tread design embodying my invention shown thereon; and Fig. 2 is a cross-sectional view taken substantially along the line II—II of Fig. 1.

I claim:

The ornamental design for a tire, as shown.

BURGESS DARROW.
